DESIGN FOR A CARDBOARD DOLL

Flora B. Baker, Grants Pass, Oreg.

Application January 15, 1944, Serial No. 112,248

Term of patent 7 years

(Cl. D34—4)

To all whom it may concern:

Be it known that I, Flora B. Baker, a citizen of the United States, residing at Grants Pass, in the county of Josephine and State of Oregon, have invented a new, original, and ornamental Design for a Cardboard Doll, of which the following is a specification, reference being had to the accompanying drawing, forming part thereof.

In the drawing:

I claim:

The ornamental design for a cardboard doll, as shown.

FLORA B. BAKER.
